INVERTER SWITCH

Harry Stuart Tice, Jr., Des Plaines, Ill., assignor to Controls Company of America, Schiller Park, Ill., a corporation of Delaware

Filed Feb. 29, 1960, Ser. No. 11,806
10 Claims. (Cl. 318—285)

This invention relates to an improved timer for washing machines or washer-dryer combinations, and particularly to a switch arrangement for controlling the direction of rotation of these devices.

This application is directed primarily to horizontal type washers, where interval timers are used to periodically reverse the direction of rotation of the drive motor for the washer during specific intervals in the program cycle. In washers of this type, continued rotation of the washer in one direction is thought to produce twisting in the clothes, and by periodically reversing the direction of rotation of the washer, tendency of the clothes to become twisted will be reduced. Reversal at the end of each basic time interval is not considered satisfactory because the duration of the intervals is too long. To produce satisfactory results, reversal must occur periodically at intervals of a duration less than provided in the basic timer.

The primary object of the present invention is to provide a switching mechanism which can be used to periodically reverse the direction of rotation of a washer independently of the interval timer.

Another object is to provide a reversing switch mechanism which can be easily integrated into an interval timer.

A further object is to provide a switch mechanism for a washer motor which can be readily adapted to washers already on the market.

A further object is to provide a switching mechanism which is simple in construction and operation, resulting in substantial manufacturing economies.

Other objects and advantages will be pointed out in, or be apparent from the specification and claims, as will obvious modifications of the two embodiments shown in the drawings in which:

FIG. 1 is a plane view of the switch mechanism with the cover removed.

FIG. 2 is taken on line 2—2 of FIG. 1 showing the cam and slider arrangement.

FIG. 3 is taken on line 3—3 of FIG. 2 showing a partial section of the slider-switch arrangement.

FIG. 4 is a partial view of the slider-switch-cam arrangement.

FIG. 5 is a circuit diagram for an independent switching arrangement.

FIG. 6 is a side elevation of a timer with the switch mechanism incorporated in the ratchet drive.

FIG. 7 is taken on line 7—7 of FIG. 6, showing the switch arrangement.

FIG. 8 shows a circuit diagram for a drive motor.

As seen in the drawings, the switching mechanism includes a base plate 10 which carries a number of single pole double throw switches 12, 14 and 16 enclosed within cover 11. The switches are biased into engagement with one set of contacts and are moved into engagement with a second set of contacts by slider 18. The bias of the switches is used to hold the slider in position for cam fol-

2

lower 20 to follow the peripheral cam surface of cam 22 mounted on motor shaft 24 and driven by timing motor 26.

The slider is positioned to slide on the surface of the base plate and is provided with arms 27, 27 having dimples 28 riding on the surface of the base to stabilize the movement of the slider to reduce the friction between the slider and the plate. The slider is limited to linear motion by boss 30 and U shaped bracket 34, which engage slot 32 and motor shaft 24, respectively. The blades A, B and C of the switches are leaf springs secured to fixed terminals 36, 38 and 40 and biased upwardly to engage contacts 42, 44 and 46. The blades engage actuators 48, 50 and 52, biasing the slider in an upper position as seen in FIGS. 1 and 3, and also holding the slider against the face of the plate. Cam follower 20 (comprising an extension of actuator 50) is shown opposite cam surface 54, but does not engage this surface, so that the blades positively engage the contacts, thus insuring adequate contact pressure. On clockwise rotation of the cam, the cam follower will ride up cam surface 56, moving the slider downward with the blades moved to a neutral or open position between the contacts. The cam follower will then ride up on cam surface 58 with the slider moving the blades into engagement with lower contacts 44, 62 and 64. Continued rotation will reverse the cycle. The switch actuators on the slider can be designed so that actuator 48 opens switch 16 before switches 12 and 14 are opened, and closes switch 16 after switches 12 and 14 are closed as required in certain induction motor circuits. The cam is designed to allow the contacts to be closed for twelve seconds, and retained in a neutral position for three seconds for a timing speed of one r.p.m. The cam surface can be cut to provide any cycle required for a particular device.

The device described above may control the direction of rotation of the drive motor by merely connecting the switches in the drive motor circuit as indicated in FIG. 5. Terminals 66 and 68 are connected across the line L1, L2 and the "start" winding is connected to terminals 70 and 72. The timer motor is connected in parallel with the start winding as shown, and the run winding is connected across terminals 36 and 38. The blades are moved from one set of contacts to the other to reverse the direction of current flow through the "start" winding. A three second delay is provided in the cam to allow the drive motor to slow down before the current is reversed, to prevent an excessive surge current from being applied to the switch contacts, and so any centrifugally operated switches may reset.

It should be obvious that the time required to fabricate this device is reduced to a minimum because the slider requires no special assembling procedure, but is merely placed in position on the end plate and retained there by the switch blades.

In integrating this reversing switch arrangement into a washer or washer-dryer combination, it is only necessary to connect the reversing switches into the program switch circuit for the washer drive motor, so that the reversing switches are only operative when the program switch is active and can be by-passed when reversing is not desired. The simplicity of this circuit connection makes the reversing switch device readily adaptable to washers and washer-dryers now on the market.

In FIGS. 6, 7 and 8, the switch mechanism is integrated into a basic interval timer having a pair of terminal boards 80 and 82, which carry program switches generally designated at 84. The terminal boards are carried between end plates 86, 88 and the switches are provided with cam followers (actually switch blades) which act on cams 90 carried on arbor 92. The arbor is journaled in the end plates for rotation and carries drive ratchet 94 which is adapted to receive impulses from the timer motor 96 through drive mechanism 98. The timer motor drives motor shaft 100, on which molded disc 102 is secured for rotation. Stepping cam 104 is secured to one side of the disc, and is used as is customary, to build up energy in the drive mechanism, and at its drop permits a rapid delivery of the energy through the drive mechanism to the arbor. Lever 106 is pivoted on post 108 and biased by spring 110 to force follower 112 into engagement with the stepping cam. Verge 114 is pivoted on the lever and is biased by spring 116 into engagement with drive ratchet 94. As cam 104 rotates, the lever will rotate clockwise against the bias of spring 110, moving the verge to the next tooth on the drive ratchet. When the follower reaches the drop portion of the cam, the lever will rotate rapidly counterclockwise, forcing the verge against the drive ratchet to advance the arbor one step. Pawl 118 is pivoted on the end plate and biased by spring 119 into engagement with the drive ratchet to prevent reverse rotation of the arbor when the verge is being advanced to the next tooth on the drive ratchet.

The reversing switch mechanism is incorporated in housing 120 with cam 122 secured to the back of disc 102 and engaged by cam follower 123 on slider 124, which is positioned to slide on housing 126. Switch actuators 128, 130 and 132 engage switch blades A, B and C on switches 134, 136 and 138, which are biased into engagement with contacts 140, 142 and 144 and hold the slider in position for the cam follower to ride on the periphery of cam 122. On rotation of the cam, the slider will move the blades into engagement with contacts 142, 146 and 148. This structure is similar to and operates the same as that described above.

The switch mechanism is connected into the circuit for the drive motor for the washer as shown in FIG. 8. Program switches 83, 85 and 87 are used to by-pass switches 134, 136 and 138 where unidirectional rotation is required during either the spin cycle or the drying cycle. In these instances, it is important to have the direction of rotation of the drive motor, as controlled by the switching mechanism, synchronized with the program switches, so that the drive motor is not rotating in one direction when the program switches call for another direction, producing an excessive torque on the drive motor. This can be accomplished when cams 104 and 122 are secured to disc 102 by aligning the drop portion of cam 104 with the cam surface on cam 122, which provides the same direction of rotation as controlled by the program switches.

This structure utilizes a single timer motor to operate both the interval timer and the switching mechanism with a relatively small increase in load on the timer. It is also possible to synchronize the program switches with the reversing switch mechanism to eliminate the production of excessive torque in the drive motor due to sudden reversals in the direction of rotation.

Although but two embodiments of the present invention have been shown and described, it will be apparent to those skilled in the art that changes and modifications may be made therein without departing from the spirit of the invention or from the scope of the appended claims.

I claim:

1. A switch device comprising, a motor, a cam driven by the motor, a cam follower confined to reciprocal motion in a plane parallel to the plane of the cam, switch means of the single blade double throw type, the blade

5 of said switch means acting on the follower to bias the follower into engagement with the peripheral edge of the cam, said blade being actuated by the reciprocal motion of the follower, the cam being formed to hold the blades in one operative position or the other operative position and to delay the movement of the blade from one position to the other for a predetermined period of time.

2. A device according to claim 1 wherein the cam follower includes means for limiting the movement of the cam follower to linear motion.

3. A device according to claim 2 including a base on which the cam follower linearly reciprocates, the blade acting to retain the follower on the base.

4. The combination with a washing machine having a drive motor and a timer of the type having a cam bank driven through a drive mechanism by a timing motor in a step-by-step manner with the cam bank operating function switches according to a prescribed sequence, said drive motor being connected in circuit with certain of said function switches, for rotation in one direction when the circuit is closed, of means for controlling the direction of rotation of the drive motor comprising, reversing switch means connected in circuit with the drive motor, means for energizing the circuit including the reversing switches and the drive motor when said circuit through the function switches and the drive motor is open, drive means for actuating the switch means including a cam rotated by the drive means and a follower limited to linear motion in a plane parallel to the plane of the cam, said switch means biasing the follower into engagement with the peripheral edge of the cam so that the linear motion of the cam actuates the switches in a predetermined sequence to periodically reverse the direction of current flow and hence rotation of the drive motor.

5. The combination with a washing machine having a drive motor and a timer of the type having a cam bank driven through a drive mechanism by a timing motor in a step-by-step manner with the cam bank operating function switches according to a prescribed sequence, said drive motor being connected in circuit with certain of said function switches for rotation in one direction when the circuit is closed, of means for controlling the direction of rotation of the drive motor comprising, reversing switch means connected in the circuit for the drive motor, means for engaging the circuit including the reversing switches and the drive motor when said circuit through the function switches and the drive motor is open, a motor means, a cam rotated by the motor means, slider means confined to reciprocal motion, said switch means biasing the slider means into engagement with the cam, said switch means being actuated by the reciprocal motion of the slider means to periodically reverse the direction of current flow and hence rotation of the drive motor.

6. The combination according to claim 5 wherein the cam is formed to hold the reversing switch means in a neutral position with the circuit including the reversing switch means and the drive motor open to allow the drive motor to slow down before the current to the drive motor is reversed.

7. The combination with a sequence timer of the type having a plurality of function controlling switches operated by a cam bank driven at timing speed by a motor through a drive mechanism including a member rotating at a speed greater than timing speed, the timing speed of the cam bank causing sequential operation of the switches at predetermined intervals, of means for providing additional functions during said intervals comprising, a cam rotating with said member at a speed greater than timing speed, slider means confined to reciprocal motion, switch means including single blade double throw switches, the blades of the switch means biasing the slider into engagement with the cam so the slider reciprocates on rotation of the cam, said switch

means being actuated by the motion of the slider, and circuit means connecting the reversing means with the function switches to increase the functions available during each interval of the timer.

8. The combination according to claim 7 including a base on which the slider reciprocates, the blades acting to retain the slider in position on the base for actuation by the cam.

9. The combination according to claim 8 wherein the slider means includes means for limiting its movement to linear motion.

10. The combination according to claim 9 wherein the cam is provided with a three level cam periphery so that the switch means is cyclically moved from one position to another with a predetermined time delay in the movement between positions.
